FIG. 3.

FIG. 4.

Inventor

Charles Catlett
Sol Shappins
Attorney

UNITED STATES PATENT OFFICE

CHARLES CATLETT, OF STAUNTON, VIRGINIA

WINDOW FRAME

Application filed March 23, 1931. Serial No. 524,742.

This invention relates to improvements in window frames, and particularly for the purpose of securing ventilation.

There have been attempts in the prior art to utilize for purposes of ventilation, the open space formed between the upper and lower sashes of a window when either or both of such sashes have been moved from their normally closed positions. In those cases where upon movement of the sashes, the top of the lower sash is above the bottom of the upper sash, the entering air is deflected and diffused without the formation of drafts. While the amount of air which passes through such an opening between the sashes depends upon the difference in pressure or temperature, or both between the outside and the inside, as well as upon other factors, the amount of fresh air which can be secured by such ventilation where the space is continually left open, is surprising large. In utilizing this feature for ventilation, when the space between the sashes is provided by raising the lower sash, there is a resulting disadvantage in that there is an open space between the bottom of the lower sash and the sill which produces an objectionable draft. Similarly the desired ventilating space between the sashes may also be provided by lowering the upper sash, but also in this instance, an objectionable draft is produced from the space between the upper portion of the upper sash and the window frame. When this ventilating space is provided by the raising of the lower window sash, the draft has been overcome by various attachments to the bottom of the frame or of the lower sash. For example, as illustrated in Figure 5 of the drawing, one such means is the mere insertion of a piece of board. In other instances of this character, the space at the bottom of the lower sash is left open and a deflector is supplied for the purpose of diffusing the air in an upward movement. But while these means have been suggested for preventing the ingress of a current of air producing a draft through the space left by opening the lower window sash, from the very nature of the opening produced by lowering the upper sash, no satisfactory attachments or arrangements have been sug-

gested for preventing the draft produced through this opening when the upper sash is lowered. The open space formed by the lowering of the upper sash is very objectionable, because observation and tests have shown that a very disagreeable down draft is produced in this manner.

Among the objects of the present invention is the production of a window frame which will permit the utilization of the space between the upper and lower sashes for ventilation by supplying the desired upward and diffused movements of air through such space, when the upper sash is lowered sufficiently for this purpose, and at the same time avoiding any objectionable opening at the top of the window space which opening would normally be formed by the lowering of the upper sash, whereby no draft is permitted through such point.

Other objects and advantages will appear from the more detailed description of this invention as given below, but it will be understood that this more detailed description is given by way of illustration only and not by way of limitation, since various changes in the structure may be made by those skilled in the art without departing from the scope and spirit of the present invention.

In connection with that more detailed description as illustrated below, there is shown in the drawing,

In Figure 1, a vertical section through a window casing with the upper and lower sashes in their normally closed positions, the casing embodying the present invention permitting the lowering of the upper sash without the production of a draft-producing space between the upper portion of the upper sash and the window frame or casing; in

Figure 2, a vertical section through a window frame similar to that shown in Figure 1, but showing the upper window sash in lowered position to produce the desired ventilating space between the upper and lower sashes without producing a draft-forming space between the upper portion of the upper sash and the window frame or casing; in

Figure 3, a fragmentary vertical section through a portion of the window frame or

casing, and the upper window sash showing a modification of the structure of Figure 1; in

5 Figure 4, a fragmentary vertical section through a portion of a window frame and a portion of the lower window sash showing a guide stop modified to produce the structure of the present invention at the bottom of the window casing.

It will thus be seen from the illustrative 10 structures given in the drawing, that the present invention is accomplished by slight inexpensive modification in the frame itself, and without substantial change in appearance in such window frame, such change actually increasing and adding to the strength 15 and rigidity of the normal window frame.

Window frames are all more or less generally of the same character, and the construction of such frames varies in but minor 20 particulars. In all such structures, there are the usual upper and lower sashes which run between guide strips, and which sashes in closed position are seated between the guide strips that normally project from the bottom 25 of the upper part of the frame as shown in the drawing. These guide strips may be an integral part of the frame, or they may be set in and in some manner attached to the window frame. As a general rule they do not 30 usually project over half an inch from the bottom of the upper part of the frame. The outside guide strip is usually referred to as the "blind stop", while the inner guide strip is usually referred to as the "parting bead".

35 The structure and objects of the present invention are desirably obtained by extension or enlargement of the blind stop and the parting bead, or either of them, so that they project for a distance sufficient to permit the space to be formed between the two window sashes by lowering of the upper sash, the extended or enlarged blind stop and parting bead, or either of them, serving at the same time to prevent the production of any 40 open space between the upper portion of the upper sash and the window frame or casing itself. In this evaluation of the blind stop and parting bead for the purposes of the present invention, the extensions or enlargements may be added to existing blind stops and parting beads on the ordinary window structure, but it is more desirable and is considered to be a preferred form of the invention to make the change as a permanent 45 change in the frame of the window itself.

The projection of the blind stop or parting bead, or both of them, for present purposes is carried far beyond what is ordinarily the case in the usual window frame at present employed. For this purpose both or either one of these guide members, but preferably the blind stop, is projected from the bottom of the upper part of the window frame a distance which is in excess of the vertical 55 thickness of the upper wooden part of the

lower sash. In order to permit as large an opening as possible, this projection should be in excess of the vertical thickness of the upper wooden part of the lower sash, plus the distance between the lower wooden part of the upper sash and the glass of the lower sash. In many window structures, as at present utilized, as little as two inches of extension will accomplish the result desired, while it will be very rare indeed that a projection of more than three inches will be needed.

Turning to a consideration of structures made in accordance with the present invention, in Figure 1, the window frame W carries the usual lower and upper sashes respectively L and U. In this structure, however, the blind stop 1 has been extended or projected downwardly for a substantial distance quite beyond that normally employed in the ordinary window frame structures. As noted above, these projected or extended blind stops are preferably made an integral part of the window frame structure, and become a permanent part thereof.

90 Referring now to Figure 2, which shows the same structure as that of Figure 1, the upper sash U has been lowered a sufficient distance to provide the ventilating space S between the lower portion of the upper sash U and the upper portion of the lower sash L. In this structure, although the upper sash U has been lowered from its normal position shown in Figure 1, no draft-producing space is formed at the upper portion of the window frame because of the extended or projected blind stop 1. Consequently with the structures of Figures 1 and 2, the desired ventilating space S between the sashes is thus provided without producing a draft-producing opening at the top of the window frame.

95 As noted above, the extent to which the blind stop 1 is extended or projected may vary, but as noted this distance should at least be in excess of the vertical thickness of the upper wooden part of the lower sash, and desirably should also be in excess of the vertical thickness of the upper wooden part of the lower sash plus the distance between the wooden lower part of the upper sash and the glass of the lower sash, since in the latter instance, a maximum ventilation space between the sashes is thus provided.

100 As noted above, if desired, both an enlarged or extended blind stop and parting bead may be employed. In the fragmentary structure illustrated in Figure 3, the blind stop 1 and parting bead 2 has each been extended to cooperate with the upper sash U. 105 This structure of Figure 3 will give results comparable with those of the structure of Figure 2, but it is preferred to utilize only an extended blind stop as the more desirable 110 form of the present invention.

- In the modification shown in Figure 4, the window frame W provided with the lower window sash L has the guide strip 3, which has been extended or projected upwardly, 5 as shown at 4. In such structure, the ventilating space S between the sashes may be provided by leaving the upper sash in place and raising the lower sash only. In this event, the extended guide strip 4 will serve 10 to close any opening that would otherwise be formed between the lower portion of the lower sash L and the window frame or sill. As described above for the extended blind stop and parting bead utilized at the top of 15 the window frame, when the extended guide strip 4 is utilized as illustrated in Figure 4, the extent of the projection utilized may similarly be determined in the same way that it is with the extended upper blind stops and 20 parting beads, that is the projection of the guide strip 4, as shown in Figure 4 of the drawing, should be in excess of the thickness of the lower wooden member of the upper window sash U, and preferably should be 25 extended a further distance equal to the distance between the wooden upper part of the lower sash and the glass of the upper sash.
- It will thus be seen that the present invention provides an inexpensive permanent 30 modification of the window frame structure itself, allowing for ventilation, and at the same time preventing any draft-producing openings due to the raising or lowering of the window sashes. In addition, by the utilization 35 of enlarged or extended blind stops or parting beads for the purposes of the present invention, the strength and rigidity of the ordinary window frame structure is improved and increased. In new constructions, 40 the permanently modified frame of the present invention as illustrated in Figures 1 to 4 may be employed, whereas in old structures where window frames are already in place, the extensions for the blind stops and part- 45 ing beads may be attached to the guide strips that are already in use on such window frame structures.
- Having thus set forth my invention, I claim:
- 50 1. In combination, a window frame and a sash operable therein, said sash having an impervious top rail, said frame having a bind stop extending vertically contiguously with the said impervious top rail of the said 55 sash for a distance greater than the vertical thickness of the center rail of said sash whereby the impervious upper rail cooperates with the extended blind stop to prevent flow of air, although a flow of air may take 60 place between the center rails of the sash.
2. In combination, a window frame and a sash operable therein, said sash having an impervious top rail, said frame having a parting bead extending vertically contiguously 65 with the said impervious top rail of the said
- sash for a distance greater than the vertical thickness of the center rail of said sash, whereby the impervious upper rail cooperates with the extended parting bead to prevent flow of air, although a flow of air may 70 take place between the center rails of the sash.
3. In combination, a window frame and a sash operable therein, said sash having an impervious top rail, said frame having a 75 blind stop and a parting bead each extending vertically contiguously with the said impervious top rail of the said sash for a distance greater than the vertical thickness of the center rail of said sash, whereby the impervious upper rail cooperates with the extended blind stop and parting bead to prevent flow of air, although a flow of air may 80 take place between the center rails of the sash.
- CHARLES CATLETT.
